UNITED STATES PATENT OFFICE

JAMES E. GILLESPIE, OF WARWICK, NEW YORK.

SUPPORTING AND OPERATING CHEMICAL FIRE-EXTINGUISHERS.

SPECIFICATION forming part of Letters Patent No. 297,687, dated April 29, 1884.

Application filed November 16, 1883. (No model.)

To all whom it may concern:

Be it known that I, JAMES E. GILLESPIE, of Warwick, in the county of Orange and State of New York, have invented a new and useful Improvement in Supporting and Operating Chemical Fire-Extinguishers, of which the following is a specification.

My invention relates to what are commonly known as chemical or "bottle-breaking" fire-extinguishers, in which pressure is generated by the combining of two or more chemicals or substances, one of which is commonly contained in the extinguisher until the latter is to be used; when the bottle is broken and the chemical or substance liberated.

The invention is applicable to extinguishers which are too large to be carried on the back and which remain stationary even when in use, the hose, which is permanently connected with them, being commonly coiled or reeled up near them and extended for use when necessary.

One object of my invention is to enable the extinguisher itself to be utilized as a rotary barrel, on which the hose may be coiled or wound, and another object of the invention is to enable the bottle to be broken or the chemical liberated by the very act of drawing off or extending the hose, whereby I reduce the time necessary to put such an extinguisher in operation.

The invention consists in the combination, with a chemical fire-extinguisher consisting of a closed cylindric vessel and a hose connected therewith and communicating with the interior thereof, of a support or bearing on which the extinguisher may rotate to enable the hose to be reeled upon it or extended for use, whereby the closed cylindric vessel constituting the chemical fire-extinguisher is made to serve as a barrel for the hose. The extinguisher might have a pivot or journal attached to its bottom; but to enable the invention to be utilized for extinguishers now in use, I provide a base-plate or piece whereon the extinguisher stands, and which has a downwardly-projecting pivot or journal fitting in a bearing or socket in a supporting bracket. Such a base-piece, in combination with an extinguisher, hose, and support, is included in my invention.

The invention also consists in a novel combination of parts, whereby the bottle will be broken or the chemical or substance released by the rotation of the extinguisher when the hose is drawn out or extended.

The accompanying drawing represents a partly sectional elevation of an extinguisher supported and capable of operation in accordance with my invention.

A designates the extinguisher, which consists of a reservoir of any suitable construction, and, B, is the hose permanently connected with the extinguisher at *a* and provided with the usual nozzle, B', in which is a stop-cock, *b*. From the top of the extinguisher there projects a stem, *c*, here shown as screw-threaded; and provided with a hand-wheel, *d*, by which it may be turned. The turning of the stem or screw *c* effects the breaking of the bottle within the extinguisher, and it is obvious that if the turning of the stem effects the breaking of the bottle, the holding of the stem stationary and the turning of the extinguisher would have a like result.

C designates a support, which may be a wall, or a pillar, and D designates a bracket strongly secured thereto and projecting outward therefrom.

E is a base-piece, which may be made of metal, and upon which the extinguisher stands. It may consist of arms radiating from a center and provided with upwardly-projecting ends *e*, which prevent the displacement of the extinguisher. It also has a downwardly-projecting journal or pivot, *f*, which fits and turns freely in a bearing, *g*, provided for it in the bracket D.

If the extinguisher were made with the view of supporting it according to my invention, the pivot or journal *f* might be rigidly attached to its bottom and the base-piece E dispensed with; but by the use of the base-piece I adapt my invention to the extinguishers now in use.

As here shown, the stem *c* projects above the hand-wheel *d* and fits in a bearing, *h*. This top bearing is here shown as formed in one end of an arm, F, which is hinged at *i*, so that it may be swung upward when it is desired to place the extinguisher on the stand or remove it therefrom. This top bearing is

not absolutely essential, but it is desirable in order to properly steady the extinguisher as it turns. On the top of the arm F is a second arm, G, hinged at *j*, and carrying a pin, *k*, which 5 projects through an aperture, *l*, in the arm F, and engages with the hand-wheel *d*, so as to preclude the turning of the wheel and the stem *c*. When it is not desired to prevent the turning of the stem *c*, the arm G may be swung 10 back, as shown in dotted lines. The pin *k* constitutes a detent to preclude the turning of the stem. When the extinguisher is at rest, all the parts occupy the positions shown by full lines, the hose B being coiled upon the extinguisher A as upon a reel. Upon the breaking out of a fire, the operator seizes the hose-nozzle and runs out with it, thus unreeling the 15 hose and turning or rotating the extinguisher. The stem *c* being held against turning by the detent *k*, the bottle will be broken by the time the hose is unreeled, and all that is now required to put the extinguisher into operation is to open the stop-cock *b*. Obviously this 20 may all be done in less time than is required to set the extinguisher in operation by the old method; and the invention is also advantageous, because by the old method the operator might, in the excitement of the moment, forget to break the bottle, and he would have 25 to drop the hose after extending it and go back to break the bottle. According to my invention delay entailed by forgetting to break the bottle is impossible, as the breaking is effected automatically by the mere act of extending 30 the hose. Obviously the turning of the stem *c* might liberate the chemical or substance in other ways than by breaking a bottle—as, for example, by inverting a receptacle or withdrawing a cork or stopper. I consider it far 35 more preferable to break the bottle by extending the hose, as that operation will not then depend on the memory of the operator; but I desire to include in my invention the supporting of the extinguisher so that it may 40 serve as a barrel for the hose, even if the bottle is to be broken by operating the stem *c* by hand, as is now necessary.

I am aware that a hose-reel has been mounted on a vertical axle or pivot so that it is capable of rotation to reel up the hose or extend it for use, and I make no claim to such reel. The novelty in my invention consists in so mounting a chemical fire-extinguisher that it may be utilized as a barrel on which to coil or 55 reel the hose.

What I claim as my invention, and desire to secure by Letters Patent, is—

1. The combination, with a chemical fire-extinguisher consisting of a closed cylindric vessel and a hose connected therewith and

communicating with the interior thereof, of a support or bearing on which the extinguisher may rotate to enable the hose to be reeled upon it or extended for use, whereby the closed cylindric vessel which constitutes the chemical fire-extinguisher may be made to serve as a barrel for the hose, substantially as herein described. 65

2. The combination, with a chemical fire-extinguisher consisting of a closed cylindric vessel and a hose connected therewith and communicating with the interior thereof, of a base-piece whereon the extinguisher may stand, and a support or bearing to which the base-piece is fitted, and whereon the extinguisher and base-piece may rotate to enable the hose to be reeled upon the extinguisher or extended for use, whereby the closed cylindric vessel which constitutes the chemical fire-extinguisher is made to serve as a barrel for the 70 hose, substantially as herein described. 75

3. The combination, with a chemical fire-extinguisher and a hose connected therewith, of a bearing or support whereon the extinguisher may rotate to enable the hose to be 80 reeled upon it or extended for use, and means for automatically liberating the chemical in the extinguisher by the rotating of the extinguisher, substantially as and for the purpose herein described. 85

4. The combination, with a chemical fire-extinguisher provided with a projecting stem, whereby the chemical is liberated, and a hose connected with the extinguisher, of a bearing or support whereon the extinguisher may 90 rotate to enable the hose to be reeled upon it or extended for use, and a detent for precluding the turning of said stem, substantially as and for the purpose herein described. 95

5. The combination, with a chemical fire-extinguisher provided with a projecting stem, whereby the chemical is liberated, and a hose connected with said extinguisher, of a base support or bearing whereon the extinguisher may rotate, a top bearing for said stem, and a 100 detent for holding the stem against turning and removable independently of said top bearing, substantially as and for the purpose herein described. 105

6. The combination, with the extinguisher A, provided with the stem *c*, and handle or wheel *d*, of the hose B, the base-piece E, the bearing *g* for said base-piece, the hinged arm F, comprising a bearing for said stem, and the secondary arm G, carrying the detent *k*, 110 all substantially as herein described. 115
